(57) CLAIM

The ornamental design for a cupcake holder, as shown and described.

DESCRIPTION

FIG. 1 is a front elevational view with the rear view being a mirror image of a cupcake holder showing my new design;

FIG. 2 is a top plan view thereof;

FIG. 3 is a bottom plan view thereof;

FIG. 4 is a right side elevational view thereof; and,

FIG. 5 is a left side elevational view thereof.

The broken line showing in FIGS. 1, 2, 4, and 5 is for illustrative purposes only, merely disclosing the types of attachments which can be used with the present design, and forms no part of the claimed design.
